MOCCASIN

Ted J. Weiss, Dover, N. H.

Application November 16, 1953, Serial No. 27,621

Term of patent 7 years

(Cl. D7—7)

To all whom it may concern:

Be it known that I, Ted J. Weiss, a citizen of the United States and a resident of Dover, in the county of Strafford and State of New Hampshire, have invented a new, original, and ornamental Design for Moccasins, of which the following is a specification, reference being had to the accompanying drawing, forming a part hereof.

The dominant features of the design reside in the portions shown in full lines.

I claim:

The ornamental design for a moccasin, as shown and described.
